UNITED STATES PATENT OFFICE

EUGENE G. REISING, OF EAST HARTFORD, CONNECTICUT, ASSIGNOR OF ONE-FOURTH TO
ALVA C. WASHBURN, OF PITTSFIELD, MASSACHUSETTS

FIREARM

Application filed November 23, 1928. Serial No. 321,492.

My invention relates more especially to that class of firearms that are commonly held in one hand and otherwise unsupported when discharged, and which are commonly referred to as pistols, and an object of my invention, among others, is the production of a pistol that shall be comparatively inexpensive to produce and that shall, at the same time, be simple in construction and particularly efficient in operation.

One form of a firearm embodying my invention, and in the construction and use of which the objects herein set out, as well as others, may be attained, is illustrated in the accompanying drawings, in which—

Figure 1 is a view in central lengthwise section through a firearm embodying my invention, the outer end of the barrel being broken off.

Figure 2 is a side view of the same.

Figure 3 is a view in section on a plane denoted by the dotted line 3—3 of Figure 1.

Figure 4 is an isometric view of the breech bolt or slide.

Figure 5 is a view of the barrel lock.

Figure 6 is a view of said lock looking from a point located at right angles to the point of view of Figure 5.

Figure 7 is an isometric view of the sear.

In the accompanying drawings the numeral 8 denotes the handle of my improved firearm or pistol, which handle is comprised in the frame that also includes a receiver 9 and a trigger guard 10. The handle has an opening

extending lengthwise thereof for the reception of a magazine 11, and a trigger 12 is pivotally mounted in the receiver and projects into the opening formed by the trigger guard. A notch 13 is formed in the upper edge of the receiver extending from side to side thereof for a purpose to be hereinafter set forth.

A barrel housing 14 is pivotally secured to the front end of the receiver and a barrel 15 projects forwardly from the receiver and has an extension 16 projecting backwardly within the housing to the back end thereof. A shoulder 17 formed on the barrel abuts the front end of the housing, as shown in Figure 1, a screw 18 constituting the pivot for the housing. The extension 16 is reduced in size

from that of the barrel, the end of said extension being formed to nicely fit a hole 19 in the back end of the housing 14. From this hole 19 forwardly the opening in said housing is enlarged to provide a spring chamber 20 in which a breech bolt spring 21 is located, one end of said spring thrusting against the back end of the chamber 20 and the opposite end of the spring thrusting against a shoulder in a breech bolt actuator 22.

This actuator is somewhat in the form of a sleeve surrounding the barrel extension 16 and normally at the forward part thereof. The under side of said actuator projects through a slot 23 formed through the under side of the housing 14, and as shown in Figure 1. A lip 24 projecting from the under side of the actuator 22 is engaged by a cross bar 25 extending between the side parts 26 comprising forwardly extending portions of a breech bolt or slide 27.

This breech bolt has a groove formed in its under surface creating cheeks 28, the bottom of said groove resting and sliding upon the upper edge of the frame and said cheeks 28 slidably fitting the sides of said frame in the upper edge thereof. The cheeks 28 together with the side parts 26 completely close the notch 13 and all of the other openings through the side of the frame in the upper edge thereof. The side parts 26 also cover the sides of the barrel housing 14 for the greater part of its length from the rear end thereof forward.

The breech bolt is provided with any ordinary form of spring retracted firing pin 29 actuated by a hammer 30 pivotally mounted in the frame in any ordinary manner and having a strut 31 pivotally attached at one end to the hammer and its opposite end engaged with a step 32 seated on a main spring 33 in a manner common to devices of this class.

A barrel lock 34 is made in the form of a pin projecting through a round hole comprising registering recesses in a lug 35 on the barrel housing and in the wall of the receiver 9 located opposite said lug and as shown in Figure 1 of the drawings. The lock has a releasing notch 36 to permit movement of

the lug 35 and enable the housing 14 to be swung on its pivot to open the rear end of the barrel. When the lock 34 is in one position the barrel may be opened, as described, but when the lock is in another position and as shown in Figure 1, a solid portion of the lock is located within the recess in the lug 35 comprising a part of the hole for the pin, and as a result the lug cannot be moved and the housing 14 cannot be swung on its pivot. A lock actuating spring 37 is seated with one end against the bottom of a hole projecting downwardly into the upper edge of the receiver 9, the opposite end of said spring thrusting against a shoulder on a detent seated on said spring and forcing said detent against a shoulder formed by a notch 38 made in the lock 34 and as shown in Figures 5 and 6 of the drawings. A disc 39 is secured to the end of the lock 34 outside of the receiver 9 and within a recess in the outer surface thereof, and as shown in Figure 2, said disc being rotatable in said recess underneath one of the side parts 26. A finger piece or button 40 is provided as a means for rotating the disc 39 to operate the bolt, said button being located under the lower edge of one of the side parts 26.

The pointed edge of the disk 39 underlies the solid portion of the breech bolt 27, and when it is desired to unlock the bolt so that it may be opened the breech bolt is moved backwardly far enough to uncover the pointed portion of said disk, and said disk is then swung on its pivot until the button 40 engages the edge of a side portion 26. This will place the lock 34 in position to release the barrel. In this position of the parts the breech bolt is held slightly retracted by the disk 39 and consequently a disconnector 45 hereinafter referred to is held in a position to prevent actuation of the sear by the trigger. It will therefore be seen that the hammer cannot be operated while the barrel is open and firing is therefore prevented at such time.

A sear 41 is pivotally mounted in an opening 42 in the receiver in which opening the hammer 30 is also mounted and from which it projects. The sear is actuated by a sear bar 43 pivotally attached at one end to the trigger 12 and extending backwardly therefrom through a groove 44 in the side of the receiver and into a position to engage the lower end of the sear. A disconnector 45 is slidably mounted in a disconnector groove 46 in the side of the sear and as upon a pin projecting from the bottom of said groove through a slot in the disconnector, and as shown in Figure 1 of the drawings. The upper end of the disconnector rests in a firing notch 47 in the under side of the breech bolt, and when in this notch, and as shown in Figure 1, a pull on the trigger will engage the back end of the sear bar 43 with the

lower end of the sear 41, thereby disengaging it from the hammer in a manner that will be readily understood. When, however, the breech bolt is moved backwardly the notch 47 will be moved out of registering position with the end of the disconnector and the latter will be forced downwardly, thereby moving the rear end of the sear bar downwardly so that it cannot be engaged with the sear.

A multiple spring is provided for the trigger and for the sear, this spring comprising a base 48 seated at its lower end in a notch in a magazine catch 49 and having intermediate its ends lugs 50 located in notches in lips projecting from the handle 8 into the magazine chamber, said lips being formed by a groove made in the wall of said magazine chamber and as shown in Figure 3 of the drawings. Said spring also comprises fingers 51-52, there being two fingers 51 projecting from the base of the spring and pressing with their upper ends against the sear bar 43 while the central and longer finger 52 presses against the sear 41 tending to force it into engagement with the notches in the hammer 30.

It will be noticed that this spring is secured to the handle intermediate its ends and the fingers at one end operate parts of the firing mechanism while the opposite end of the spring acts to hold the magazine catch 49 in position to secure the magazine in place.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim—

1. A firearm including a frame, a barrel mounted on top of the frame and pivotally attached thereto at one end to effect downward movement of the front end of the barrel and upward swinging movement of the rear end of the barrel to open the breech, and a breech-bolt slidably mounted on the frame back of the barrel and having upwardly extending side pieces spaced apart and open at the top between which the rear end of the barrel is located.

2. A firearm including a frame having a magazine chamber therein, a magazine catch to engage and retain the magazine in said chamber, a sear, a trigger, a spring having branches at one end to act upon said sear and trigger, the opposite end of said spring being supported by said catch upon which said spring acts, and means independent of

said catch for removably attaching said spring to the frame.

3. A firearm including a frame, a barrel pivotally mounted in the frame, a lock rotatably mounted to engage said barrel to retain it in its closed position, and a spring pressed detent exerting force to move said lock in one direction and also engaging said lock to retain it in place by preventing 10 lengthwise movement thereof.

4. A firearm including a frame, a barrel pivotally mounted in the frame, a rock rotatably mounted in the frame to engage said barrel to retain it in its closed position, a 15 plate secured to said detent in a recess on the outer surface of the frame, and a finger on said plate projected to engage the end of said barrel to limit rotating movement of said lock.

20 5. A firearm including a frame, a barrel supporting member movably mounted on the frame and having a spring housing therein, a spring located in said housing, a breech-bolt slidably mounted on the frame, and a 25 member located in said housing and projected therefrom to engage said breech-bolt, whereby force of the spring is exerted upon said bolt.

30 6. A firearm including a frame, a barrel supporting member movably mounted on the frame and having a recess with a slot in the bottom thereof, a barrel projecting into said supporting member and closing the mouth of said recess, a breech-bolt slidably 35 mounted on the frame, and a member slidably mounted in said recess and projecting into engagement with said breech-bolt for exertion of said spring on said bolt.

40 7. A firearm including a frame, a barrel pivotally mounted on the frame, a lock to hold the rear end of the barrel in closed position, a finger on said lock located in the path of movement of a breech-bolt to prevent the latter from closing when the barrel 45 is unlocked, and the breech-bolt slidably mounted on said frame, for said engagement of said finger.

50 8. A firearm including a frame, a barrel pivotally mounted on the frame, a lug projecting from the barrel, a rotatably mounted lock to engage said lug to lock the barrel in its closed position, a rotating plate secured to said lock in a recess in said frame inside of side parts projecting forwardly from a 55 breech-bolt, the breech-bolt slidably mounted on said frame, and a finger on said plate located in the path of movement of the breech-bolt to prevent it being closed before the barrel is in its closed position.

60 EUGENE G. REISING.
